Cell-O Corporation, Detroit, Mich., a corpora-
tion of Michigan

Application August 12, 1937, Serial No. 158,639

15 Claims. (Cl. 299—107.6)

The present invention relates to improvements in nozzles adapted particularly for delivering timed metered injections of liquid fuel in connection with the operation of internal combustion engines.

One of the important objects of the present invention is to provide a novel fuel injection nozzle in which proper atomization of the fuel and maximum penetration consistent therewith of the issuing jet or spray into the combustion space are obtained at all rates of injection.

Another object is to provide a new and improved plain orifice nozzle in which the manner of approach of the fuel to the orifice is varied to change the discharge characteristics in accordance with changes in the rate of injection.

A further object is to provide a novel plain orifice nozzle in which the coefficient of discharge of the orifice is controlled by the flow of the fuel.

A more specific object is to provide a new and improved fuel injection nozzle with a plain discharge orifice in which the fuel is caused to issue from the orifice as a jet or spray varying progressively from a centrifugal form to a non-centrifugal form in the course of the valve opening movement, whereby the coefficient of discharge and hence the flow capacity of the orifice are progressively increased to obtain the required dispersion and penetration characteristics not only at maximum rates of delivery but also at low and medium rates of delivery.

Still another object is to provide a novel flow-controlled fuel injection nozzle with a plain discharge orifice in which initial, intermediate and final flow restrictions of progressively increased flow areas are successively effective to set up opening pressure assistances in the course of the valve opening movement, and in which the intermediate restriction is also effective within its range to vary the coefficient of discharge of the orifice as required to maintain a proper injection pressure at low and medium rates of delivery.

Further objects and advantages will become apparent as the description proceeds.

In the accompanying drawing,

Figure 1 is a longitudinal sectional view of a nozzle tip embodying the features of my invention.

Figs. 2 and 3 are transverse sectional views taken respectively along lines 2—2 and 3—3 of Fig. 1.

Figs. 4 and 6 are fragmentary longitudinal sectional views of two modified forms of nozzle tips embodying the general features of the invention.

Fig. 5 is a detail sectional view taken along line 5—5 of Fig. 4.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

The present invention is an improvement of the nozzle disclosed in my copending application, Serial No. 152,074 filed July 6, 1937.

Referring more particularly to the drawing, the fuel injection nozzle illustrated in Figs. 1 to 3 comprises a suitable body or housing 11. Preferably, the body 11 is in the form of a tubular shell defining an axial bore 12, and having an external peripheral flange 13 at the base end and an internal peripheral flange 14 at the discharge end.

The discharge end of the shell 11 is closed by an orifice head 15 which has suitable orifice means with the desired fuel discharge characteristics, and which preferably is removable to permit substitution for different spray patterns and characteristics. The orifice head 15 may be provided in any desired form, and in the present instance is shown as a circular plate or block extending snugly through and beyond the flange 14, and having an external peripheral mounting flange 16 seating snugly within the bore 12 against the inner face of the flange 14.

A generally tubular spacer 17, having an inner peripheral flange 18 at the outer end defining an axial guide bore 19, is removably fitted into the shell 11 and serves to hold the plate 15 in position. Removably positioned against the inner end of the spacer 17 is a tubular valve body 20 having an inner peripheral end flange 21.

A stationary member 22 in the form of a cylindrical valve plug is removably fitted into the base end of the shell 11 against the body 20, and serves to hold the various parts within the shell 11 in assembled position. Suitable plastic means 23 may be pressed into an annular groove 24 having opposed complementary sections in the base end of the shell 11 and the member 22, and serves to seal and maintain the assembly. The member 22 is formed with an axial fuel inlet passage 25 adapted for a fluid-tight connection with a fuel pump or other suitable means (not shown) for supplying the fuel to be injected.

It will be understood that the assembly just described constitutes the rigid structure of the nozzle tip, and as such is adapted to be connected to the source of fuel supply, and to be clamped or secured to the engine at the desired point of injection. A nozzle holder or other suitable means, not specifically disclosed herein since per se it forms no part of the present invention, may be utilized for this purpose as is well understood in the art. The rigid structure of the nozzle tip is susceptible of various modifications and alternative forms without departing from the broad aspects of the present invention, and in general provides an internal chamber 26, defined by the spacer 17 and the body 20, and adapted for communication with the inlet passage 25 and to discharge through the orifice body 15.

The supply of fuel under pressure, from the inlet passage 25 to the chamber 26 for injection through the orifice head 15 into the combustion space, is under the control of a nozzle valve 27. Within the broad aspects of the invention, the valve 27 may be of any suitable form or character. In the present instance, the valve 27 is spring seated against the pressure of the fuel, and opens outwardly in the direction of the fuel flow. More particularly, the valve 27 comprises a flat annular valve seat 28 formed in the inner end of the valve plug 22, and encircling a valve passage 29 opening from the passage 25. A movable valve member 30, herein shown in the form of a partial or half ball, has a flat valve face 31 adapted for engagement with the seat 28. When the valve member 30 is seated, the seat 28 defines a central pressure area A_v on the face 31 exposed to the fuel pressure in the passage 29.

Any suitable means may be provided for supporting the valve member 30, and in the present instance this means comprises a retainer 32 in the form of a circular head slideably guided in the valve body 20 and rigid with the inner end of an axial stem 33 guided in the bore 19. To permit self-alignment with the valve seat 28, the spherical portion of the valve member 30 is seated for universal adjustment in a partial spherical socket 34 formed in the free end face of the retainer head 32. A coiled compression spring 35 closely encircles the stem 33, and abuts at opposite ends against the spacer flange 18 and the head 32 to urge the valve member 30 toward or against the valve seat 28 with a predetermined spring pressure.

The valve member 30 is reciprocably disposed within the confines of the flange 21, and coacts therewith to define an annular flow passage 36. Formed in the periphery of the head 32 are a plurality of longitudinal flutes 37 (see Fig. 2) which provide unrestricted flow passages from the passage 36 to the chamber 26 about the stem 33. The outer end portion of the stem 33 is formed with a peripheral groove 38 defining a head 39 slideable with a close fit in the outer end of the bore 19, and is also formed on the periphery with a plurality of longitudinal flats 40 (see Fig. 3) defining flow passages opening from the chamber 26 to the groove 38. A plurality of grooves 41 in the periphery of the head 39 serve to connect the groove 38 to the orifice means in the orifice head 15. It will be understood that the flow path of the fuel from the valve 27 to the orifice head 15 leads through the passage 36, the flutes 37, the chamber 26, the passages along the flats 40, the groove 38 and the grooves 41.

Upon the application of fuel pressure from any suitable source of timed delivery of metered fuel quantities, static pressure is first applied to the area of the ball element 30 exposed to the valve passage 29 at the valve seat 28, i. e., the valve opening pressure area A_v . When the hydraulic pressure times the area A_v overbalances the pressure of the spring 35, the valve 27 will open to permit the flow of fluid to the orifice head 15 at which point hydraulic pressure is again built up by reason of the orifice restriction.

The opening of the valve 27 is made at least in part responsive to the rate of fuel flow so that the applied hydraulic pressure may be limited and controlled as desired throughout the range of valve movement. More particularly, a plurality of flow restrictions or resistances of different flow areas are interposed in the path of fuel flow, and are successively effective over different portions of the injection range in the opening and closing movements of the valve 27. Each of these restrictions when in control tends to build up a differential pressure responsive to the rate of flow and separate from the injection pressure and acting on a lifting area A_d larger than the valve opening area A_v . By reason of this difference in area, a relatively small pressure differential is required to move and hold the valve 27 open, and hence the remaining pressure of the total applied pressure is relatively high and is utilized solely for injection purposes to obtain the desired atomization and penetration. The subdivision of the pressure to perform the separate functions makes possible a heavy lifting action without objectionably disturbing the injection characteristics of the nozzle.

Each flow restriction in coaction with the associated pressure area sets up a valve opening pressure assistance. In the present instance three assistances A, B and C have been provided. It will be understood that the flow restrictions may be provided in any suitable manner, and may be varied widely in form and character depending on the operating characteristics desired.

The assistance A is in control when the valve member 30 is in close proximity to the seat 28, and causes the initial opening movement and the final closing movement of the valve 27 to occur with extreme rapidity. It is transient or disappearing in character in the opening movement of the valve 27. To obtain the assistance A, the annular valve seat 28 is peripherally relieved by an encircling groove or recess 42 formed in the plug 22, thereby providing a small seat area. As a result, the seat pressure is sufficiently high to collapse or extrude the oil film between the valve faces when the valve 27 is closed. The bottom of the groove 42 is inclined outwardly toward the face 31 of the valve member 30, and coacts with the peripheral edge of the latter to define a small annular flow restriction 43. By inclining the bottom of the groove 42, the seat 28 is conveniently provided with a substantial relief, and the effective minimum area or clearance of the small flow restriction 43 may be readily and accurately determined by the use of mathematics, the depth of the seat relief, the angle and the radial dimensions of the half ball 30 and seat 28 being known. The bottom of the groove 42 being closely spaced from the peripheral edge of the half ball 30 also serves approximately to square up the latter with the seat 28. Hence, the half ball 30 cannot en-

gage the seat 28 at an angle sufficiently large to cause damage or result in valve leakage.

When the hydraulic pressure from the source of supply acting on the closed valve area A_v is sufficient to overcome the force of the spring 35, the valve 27 will open. After the initial opening movement, the annular restriction 43 builds up a pressure differential which is applied to the flat face area 31 of the valve member 30, and which assists the initial force to accelerate rapidly the first portion of the valve movement, so that the valve member 30 is caused to leave the seat 28 with a popping action. Since the area 31 is much larger than the valve area A_v , the differential pressure required to move the valve member 30 is considerably lower than the valve opening pressure, and makes available immediately a high pressure for injection with proper atomization. If the valve opening movement continues, as for the delivery of large quantities of fuel, the initial assistance A, quickly disappears, thereby reducing the pressure drop at the seat and releasing more pressure for injection. The assistance A also serves to accelerate rapidly the final closing movement of the valve 27. As the valve member 30 moves into close proximity to the seat 28, the restriction 42 again becomes effective, and sets up a differential pressure acting on the ball area 31 in opposition to the closing movement. However, when the rate of flow drops to a point where the assistance A is no longer effective to balance the closing force, the spring 35 will move the valve member 30 rapidly toward the seat 28 to close the valve 27 with a popping action.

The assistance B becomes effective after disappearance of the assistance A, and serves to control the transition from the slowest rates of delivery to medium rates of delivery. To obtain this assistance, the grooves 41 are formed to define a flow restriction tending to set up a differential pressure acting outwardly on an effective area equal to the transverse area of the stem 33. As the head 39 moves outwardly of the bore 19 in the opening movement of the valve 27, the effective length of the grooves 41 is shortened, thereby reducing the flow restriction. Hence, the assistance B also is transient or disappearing in character so as to be effective only over the intermediate range of injection.

The final assistance C becomes effective after disappearance of the assistance B, and hence controls the transition from medium rates of delivery to maximum rates of delivery. To obtain this resistance, the clearance between the flange 21 and the peripheral edge of the valve member 30 is small so that the passage 36 defines a flow restriction tending to set up a differential pressure acting outwardly on the face 31. It will be understood that the valve may open to any point in the range of movement depending on the rate and quantity of injection. The assistances A, B and C would be relatively so proportioned as to cooperate to obtain the desired result. For further details as to the function and operation of the assistances A, B and C, reference may be had to the aforesaid copending application.

The orifice head 15 may be provided in various forms depending on the spray characteristics desired. In Fig. 1, the head 15 is formed in the inner face with an injection pressure chamber 44 which registers with the bore 19 to receive the head 39 in the opening movement of the valve 75

27, and which opens axially to a single plain hole discharge orifice 45. Preferably, the free end of the head 39 and the walls of the chamber 44 are tapered or stream-lined in the direction of fuel flow.

One of the important features of the present invention is to vary the discharge characteristics of the orifice 45 in accordance with the rate of fuel flow so as to obtain proper atomization and penetration at all rates of delivery, and particularly to permit the delivery of very small quantities of fuel without the presence of objectionable solids through a fixed orifice otherwise of sufficient size for maximum injection. This is accomplished by changing the manner of approach of the fuel to the orifice 45 whereby to vary the coefficient of discharge as required. The degree of atomization is a function of the pressure applied at the orifice, and the pressure varies as the square of the velocity times the coefficient of discharge. If this coefficient is constant, the pressure at low rates of delivery may be too low to break up the fuel. By varying the coefficient, an effect comparable to a variation in the size of the orifice is obtained.

To control the coefficient of discharge of the orifice 45, a variable centrifugal action is imparted to the entering fuel. In Fig. 1, the centrifugal action is obtained by means of the grooves 41 which preferably are V-shaped and of suitable flow area and proportions in cross-section, and which are formed with a suitable helical lead to impart a swirl to the fuel passing therethrough. The swirl of the fuel reduces the coefficient of discharge, and hence builds up an injection pressure in the chamber 44 sufficient to effect proper atomization. Since the head 39 moves outwardly into the chamber 44, the effective length of the grooves 41 is progressively decreased in the course of the valve opening movement. Hence, the coefficient of discharge is the lowest at minimum rates of delivery and increases progressively through the range of the assistance B. Upon movement of the peripheral groove 38 into direct communication with the chamber 44, the grooves 41 cease to be effective, and the fuel jet issuing from the orifice 45 becomes non-centrifugal. The assistance C accomplishes the last step in removing the centrifugal action to whatever extent it is to be removed depending upon the particlar penetration and dispersion characteristics required.

The groove belt defined by the head 39 has a close and uniform sliding fit with the bore 19 so that the grooves 41 will have maximum effectiveness in defining the flow passages therethrough and in varying their restrictive action with changes in the valve lift.

The spiral grooves 41 should have a flow area sufficiently restricted to make the assistance B effective, but not restricted to an extent resulting in interference with the proper functioning of the assistance A.

The helix angle of the grooves 41, i. e. the lead along the stem axis, may be varied within limits depending on the atomization and penetration characteristics desired, without departing from the invention. Ordinarily, the helix angle should be the maximum consistent with desired atomization at low rates of injection. Decreasing the helix angle results in a greater centrifugal action and a corresponding decrease in the coefficient of discharge. A greater cone spray angle, with increased atomization, is thereby obtained, and the jet penetration is decreased. In

creasing the helix angle results in a smaller spray cone angle and increased jet penetration.

Figs. 4 to 6 illustrate various modified forms eliminating stream-lining and having different types and arrangements of discharge orifices. In all other respects, these modified forms are the same as the form of Figs. 1 to 3, and the same reference characters are therefore employed to identify corresponding parts.

In the form of Figs. 4 and 5, the head or groove belt 39 is cylindrical throughout its length and flat at the end, and the chamber 44 is similarly shaped. A plurality of discharge orifices 45b, for example two diametrically spaced orifices, open from the chamber 44 to discharge radially from the orifice head 15. To provide the orifices 45b, two radial bores 46 are formed in opposite sides of the head 15 adjacent the exterior of the flange 14, and at their inner ends longitudinally intersect the outer end surface of the chamber 44. Bushings 47 with axial apertures defining the orifices 45b are tightly fitted into the outer ends of the bores 46.

The coefficient of discharge of the orifices 45b is controlled in the same manner as in Fig. 1. During low rates of delivery, the groove 41 impart a centrifugal action to the fuel entering the chamber 44. The centrifugal action in the chamber 44 imparts to the fuel entering the bores 46 a secondary swirl about each of the orifice axes. In the full opening movement of the valve, the fuel issues from each orifice 45b first in the form of a centrifugal envelope of progressively diminishing cone angle, and then in the form of a non-centrifugal spray or jet.

The form of Fig. 6 is exactly like that of Figs. 4 and 5 with the exception that the two radial orifices 45c open directly from the chamber 44 and along diverging axes. In these various forms, the coefficient of orifice discharge is flow-controlled as described. By reason of the flat transverse end faces of the head 39 and the chamber 44, a softer non-centrifugal jet is obtainable than in the stream-lined form of Figs. 1 to 3.

I claim as my invention:

1. In a fuel injection nozzle, in combination, a body having a fuel inlet and a fixed cylindrical hole discharge orifice of constant restricted flow area and length, spring seated reciprocatory valve means for controlling the supply of fuel under pressure for discharge through said orifice, and means fixed with said means for effecting a centrifugal approach of the fuel to said orifice and for varying the angle of said approach progressively in direct response to changes in the degree of valve opening so as to alter the spray characteristics for different rates of delivery and to vary the coefficient of discharge of said hole orifice.

2. In a fuel injection nozzle, in combination, a body having a fuel inlet and a fixed discharge orifice of constant restricted flow area, spring seated reciprocatory valve means for controlling the supply of fuel under pressure for discharge through said orifice, and means movable positively with said valve means and operable in direct response to the opening movement of said valve means to cause the fuel to issue through said orifice initially in the form of a centrifugal envelope of progressively decreasing cone angle and finally in the form of a non-centrifugal spray.

3. In a fuel injection nozzle, in combination, a hollow body having a central chamber with a plain hole discharge orifice at one end and an inlet passage at the other end, means defining

an annular valve seat at the discharge end of said passage, a clearance groove encircling said seat and having a bottom inclined outwardly toward the plane of the seat face, a valve head 5 movable in said chamber and coacting therewith to define a flow restriction, a valve element mounted for self adjustment on said head and having a flat area disposed for engagement with said seat and coacting with the bottom of said groove to define another flow restriction when said valve element is in close proximity to said seat, spring means acting on said head in a direction to move said valve element toward said seat, and means movable with said head and coacting with the inlet of said discharge orifice to cause the emission of the fuel first in the form of a centrifugal envelope and then in the form of a non-centrifugal core as said valve element moves into fully open position.

4. In a fuel injection nozzle, in combination, a body having a circular chamber with an axial inlet bore opening thereto, a spring-seated valve for controlling the supply of fuel to said bore and opening in the direction of fuel flow, a head movable with said valve and slidable with a close fit progressively into and out of the outlet end of said bore, a plurality of helical grooves formed in the periphery of said head and opening to the opposite ends thereof, said head when in said bore coacting with said bore to constitute said grooves restricted flow passages in the path of fuel flow from said bore to said chamber variable in effective length in accordance with the extent of valve opening, said passages being adapted to impart a centrifugal action to the fuel in said chamber and to build up a differential pressure acting as a valve opening assistance, and a fixed discharge orifice opening axially from said chamber.

5. In a fuel injection nozzle, in combination, a body having a chamber with an inlet passage opening thereto, spring-seated valve means for controlling the supply of fuel to said passage and opening in the direction of fuel flow, a head 45 movable with said valve means and slidable with a close fit progressively into and out of the outlet end of said passage, an inclined groove formed in the periphery of said head and opening to the opposite ends thereof, said head when in said passage coacting with said passage to constitute said groove a flow restriction in the path of fuel flow from said passage to said chamber variable in effect in accordance with the extent of valve opening, said restriction being adapted to impart a centrifugal action to the fuel in said chamber and to build up a differential pressure acting as a valve opening assistance and tending to move said head outwardly of said passage, and a discharge orifice opening from said chamber.

6. In a fuel injection nozzle, in combination, a body having a chamber with a fuel inlet, valve means for controlling the supply of fuel to said inlet, a head movable with said valve means and slidable with a close fit progressively out of said inlet into said chamber, said head being constructed to coact with said inlet when therein to define a restricted flow passage along said head setting up a resistance to flow variable in effect in accordance with the position of said head in said inlet and arranged to direct the fuel centrifugally into said chamber, said passage being ineffective when said head is positioned out of said inlet, and a restricted pressure injection orifice opening from said chamber.

7. In a fuel injection nozzle, in combination,

a body having a chamber with a fuel inlet, valve means for controlling the supply of fuel to said inlet, a head movable with said valve means and slideable with a close fit progressively into and out of said inlet, said head being constructed to coact with said inlet to define a restricted flow passage means along said head when in said inlet to set up a resistance to flow, said passage means being variable in effective length in accordance with the position of said head in said inlet and arranged to direct the fuel centrifugally about said chamber, and a plurality of fixed restricted pressure injection orifices opening from said chamber.

8. In a fuel injection nozzle, in combination, a body having a chamber with a fuel inlet, valve means for controlling the supply of fuel to said inlet, a head movable with said valve means and slideable with a close fit progressively into and out of said inlet, said head being constructed to coact with said inlet to define a flow restriction variable in effect in accordance with the position of said head in said inlet and to direct the fuel centrifugally into said chamber, and a plurality of bores opening from said chamber along elements of a cone having its axis in said nozzle, and constituting plain hole discharge orifices.

9. In a fuel injection nozzle, in combination, a hollow body having an inner chamber with a fuel inlet at one end and a fixed discharge orifice at the other end, a spring seated valve for controlling the supply of fuel through said inlet to said chamber and opening in the direction of fuel flow, and means for defining a plurality of peripherally inclined restricted flow passages in said inlet decreasing progressively in effective length in accordance with the opening movement of said valve for causing the fuel to enter said orifice centrifugally.

10. In a fuel injection nozzle, in combination, a hollow body having an internal chamber with a fuel inlet and having a second chamber with an outlet orifice and separated from said internal chamber by a connecting passage, a spring seated valve for controlling the supply of fuel from said inlet to said internal chamber and having a valve stem guided in said passage, the free end portion of said stem being formed with an annular groove in communication with said internal chamber and movable into and out of communication with said second chamber and defining a head projecting into said second chamber, a plurality of restricted helical grooves formed in the periphery of said head and establishing communication between said annular groove and said second chamber, said helical grooves being effective to impart a progressively decreasing centrifugal action to the fuel during the first portion of the valve opening movement and then becoming ineffective upon movement of said annular groove into communication with said second chamber to permit a non-centrifugal fuel flow to said orifice during a subsequent portion of said valve opening movement.

11. In a fuel injection nozzle, in combination, a hollow body having a fuel inlet, an orifice head mounted on said body and having a central fixed discharge orifice and an outlet chamber opening to and tapered toward said orifice, means in said body defining a central chamber and a guide bore connecting said chambers, a spring-seated valve for controlling the supply of fuel from said inlet to said central chamber and opening in the direction of fuel flow, a stem on said valve guided in said bore and having a

head movable with a close sliding fit from said bore progressively into said outlet chamber, a plurality of restricted grooves formed in and opening along the periphery of said head and being helically inclined, means defining a primary flow restriction when said valve is in proximity to closed position and creating a differential pressure upon fuel flow to impart an initial transient valve opening assistance, said inclined grooves constituting a second flow restriction effective after said primary restriction and creating a differential pressure upon fuel flow to impart a second valve opening assistance, and means defining a third flow restriction effective after said second restriction and creating a differential pressure upon fuel flow to impart a valve opening assistance as said valve continues movement toward full open position.

12. In a fuel injection nozzle, in combination, 20 a casing having fuel inlet means and a restricted discharge orifice, spring-seated valve means controlling the supply of fuel from said inlet means and having a relatively small valve area exposed when seated to the inlet pressure and a relatively large lifting area exposed to the inlet pressure upon initial opening of said valve means, and flow restriction means independent of the flow area through said valve means located in the flow path to said orifice and operable to provide a differential pressure acting on said lifting area, said restriction means in the opening movement of said valve means directing said fuel to said orifice first centrifugally and then non-centrifugally to vary the coefficient of discharge.

13. In a fuel injection nozzle, in combination, a body having a chamber with a fuel inlet, valve means for controlling the supply of fuel to said inlet, a head movable with said valve means and slideable with a close fit progressively into and out of said inlet, said head being constructed to coact with said inlet to define a restricted flow passage along said head variable in effect in accordance with the position of said head in said inlet and arranged to direct the fuel centrifugally about said chamber, and a plurality of peripherally spaced bores formed in said body and extending transversely of said head and being intersected tangentially by said chamber, each of said bores having an axial discharge orifice with a conical inlet, whereby the swirling fuel in said chamber is caused to enter and swirl in said bores and to discharge from said orifices in a centrifugal spray.

14. In a fuel injection nozzle, in combination, a body having a chamber with a fuel inlet, valve means for controlling the supply of fuel to said inlet, a head movable with said valve means and slideable with a close fit progressively into and out of said inlet, said head being constructed to coact with said inlet to define a restricted flow passage along said head variable in effect in accordance with the position of said head in said inlet and arranged to direct the fuel centrifugally about said chamber, and a bore formed in said body and extending transversely of said head and being intersected tangentially by said chamber, said bore having an axial discharge orifice, whereby the swirling fuel in said chamber is caused to enter and swirl in said bore and to discharge from said orifice in a centrifugal spray.

15. In a fuel injection nozzle, in combination, a body having a fuel chamber with a fuel inlet and with a fixed restricted injection orifice discharging therefrom, said chamber being tapered

toward said orifice, valve means for controlling the supply of fuel to said inlet, a head movable with said valve means and slidably with a close fit in said inlet for movement progressively from said inlet into said chamber as said valve means opens and movable from said chamber into said inlet as said valve closes, said head and said inlet being formed to define a restricted flow passage along said head setting up a resistance to

flow variable in effect in accordance with the position of said head in said inlet and arranged to direct the fuel centrifugally into said chamber, said passage being ineffective when said head is positioned in said chamber fully out of said inlet, the outer end of said head being tapered toward said orifice.

CARROLL R. ALDEN.
